UNITED STATES PATENT OFFICE

169,937

LIGHTER FUEL FILLER

William H. Gey, Boston, Mass.

Application October 9, 1952, Serial No. 21,771

Term of patent 7 years

(Cl. D58—17)

To all whom it may concern:

Be it known that I, William H. Gey, a citizen of the United States and a resident of Boston, in the county of Suffolk and the Commonwealth of Massachusetts, have invented a new, original, and ornamental Design for a Lighter Fuel Filler, of which the following is a specification, reference being had to the accompanying drawing, forming a part hereof.

The figure of the drawing is a perspective view of a lighter fuel filler showing my new design. The sides not shown are the same as the side shown.

I claim:

The ornamental design for a lighter fuel filler, as shown and described.

WILLIAM H. GEY.
